DESIGN FOR A PHONOGRAPH OR THE LIKE

Harvey L. Everett, Mount Vernon, N. Y.

Application September 23, 1946, Serial No. 133,500

Term of patent 7 years

(Cl. D56—4)

To all whom it may concern:

Be it known that I, Harvey L. Everett, a citizen of the United States of America, residing at Mount Vernon, in the county of Westchester and State of New York, have invented a new, original, and ornamental Design for Phonograph or the like, of which the following is a specification, reference being made to the accompanying drawing, forming a part thereof.

Fig. 1 is a front elevational view of a phonograph or the like, showing my new design.

Fig. 2 is a top plan view of Fig. 1.

Fig. 3 is a right hand side view of Fig. 1.

Fig. 4 is a rear view of Fig. 1.

The characteristic features of my design reside in the portions shown by means of full lines in the drawing.

I claim:

The ornamental design for a phonograph or the like, substantially as shown and described.

HARVEY L. EVERETT.
